Attorneys.

UNITED STATES PATENT OFFICE.

WILBUR H. NICHOLAS, OF INDIANAPOLIS, INDIANA.

SACK HOLDER.

Application filed December 15, 1927. Serial No. 240,137.

The object of this invention is to provide a simple, durable and inexpensive sack-holder which will have holding attachment to the top of a sack in a manner to support the sack and hold it in a taut wide-open condition at the mouth without the aid of hooks while the sack is being filled to fullest capacity with either light or heavy material.

A further object is to provide such a sack holder which may be easily adjusted to hold sacks of different diameters and lengths with the bottom of the sack always resting on the floor.

The object also is to provide a holder which which will permit a filled sack to be taken off from either side of the holder and which will be on runners thereby making the sack holder easily portable.

I accomplish the above and other objects which will hereinafter appear, by the means illustrated in the accompanying drawing, in which—

Fig. 1, is a perspective view of an empty holder ready for the placing thereon of a sack to be filled, and Fig. 2, is a view of the holder in side elevation with a sack supported by it in position to be filled.

The base of the sack holder comprises two sled-runner-like members each comprising a horizontal floor-contacting bar 3, turned up in curves 4 and 5 at its ends and continued in uprights 5 and 6. These base members are formed out of spring metal and they are rigidly connected at the upper ends of the uprights 5 and 6 by respective horizontal bars 7 and 8. The joined ends may be welded together or bolted or riveted as shown.

Bolted or otherwise rigidly secured to the middles of each of the bars 7 and 8, are the standards 9 and 10, to each of which is riveted a pair of spaced apart short clamping bars 11 and 12, which are formed with bolt holes in each end. The standards 9 and 10 are bowed outwardly at 13, between bars 11 and 12.

Short bars 14 and 15 are connected by bolts with the bars 11 and 12, at both standards 9 and 10, and complete clamps by which the respective vertical bars 16 and 17 are adjustably secured to the standards 9 and 10.

The bows 13 in the standards aid the clamps in frictionally holding the bars 16 and 17 at the given vertical adjustment of these bars.

Cross bars 18 and 19 are rigidly riveted to the upper ends of the respective bars 16 and 17. They serve to attach the bars 16 and 17 to the sack 20 and to hold the mouth of the sack

open. The lower ends of bars 16 and 17 are bent out at 21 to form stops which contact the lower clamps and keep the bars from drawing entirely out of the device on adjustments. The bars 9, 10, 16 and 17 are made of spring metal.

The operation of my invention is as follows:

The clamps are loosened and the vertical bars 16 and 17 are raised or lowered as required by the length of the sack, so the bottom of the sack will rest upon the floor when its top is properly engaged by cross bars 18 and 19. The lengths of base members 3 considerably exceed the major diameter of the largest sacks likely to be held and filled so the standards and uprights supporting cross bars 18 and 19 must be sprung inwardly to the sack. In placing a sack in the holder the sacking material is folded out and down and the bars 18 and 19 are slipped up under the fold, with the result that when the parts are released the resiliency of the uprights draws the mouth of the sack taut around the bars 18 and 19 and the bars hold the mouth of the sack open.

It is apparent that unobstructed access to the sack for filling and for removal is afforded by the device and that the bends 4 and 5 give sled runner action to the device when movement from place to place is required.

Having thus fully described my invention what I claim as new and wish to secure by Letters Patent of the United States, is—

1. In a sack holder, a pair of upright spaced apart spring-bars each having top cross bars at their upper ends over which cross-bars the folded top of a sack is secured, a base comprising a pair of horizontal spring bars each having both of their ends extended upwardly, horizontal bars connecting the ends of the upward extensions, a vertical standard attached to each horizontal end bar and means for adjustably securing a respective upright spring-bar to a vertical standard.

2. In a sack holder, a pair of upright spaced apart spring-bars each having top cross bars at their upper ends over which cross-bars the folded top of a sack is secured, a base comprising a pair of horizontal spring bars each having both of their ends extended upwardly, horizontal bars connecting the ends of the upward extensions, a vertical standard attached to each horizontal end bar, a pair of spaced apart clamps for each standard adjustably securing an upright spring bar to a respective one of the vertical standards said vertical standards having bent portions between its

pair of clamps frictionally contacting the adjacent upright.

3. In a sack holder, a pair of upright spaced-apart spring-bars each having top cross-bars at their upper ends over which cross-bars the folded top of a sack is secured, a base comprising a pair of horizontal spring bars having their ends extended upwardly by curved bends, horizontal bars connecting the ends of the upward extensions, a vertical

standard attached to each horizontal end bar, a pair of spaced apart clamps for each standard adjustably securing an upright spring bar to a respective one of the vertical standards, said vertical standards having bent portions between its pair of clamps frictionally contacting the adjacent upright. 15

In testimony whereof I affix my signature.

WILBUR H. NICHOLAS.
